REFRIGERATION APPARATUS

Samuel E. Bickle, Highland Park, Mich., assignor
to Borg-Warner Corporation, Chicago, Ill., a
corporation of Illinois

Application May 10, 1939, Serial No. 272,872

3 Claims. (Cl. 62—89)

This invention relates to refrigeration apparatus and has particular reference to condensers for refrigerating machinery. More particularly the invention relates to stacks as applied to refrigerating condensers for increasing the natural draft over the condenser and, therefore, for increasing the efficiency of the condenser.

It is an object of this invention to provide a novel form of stack for a refrigerator condenser which will be both light and easily constructed.

It is another object of this invention to provide a novel means for attaching a flexible stack to a refrigerator cabinet.

It is another object of this invention to provide a stack for a refrigerator cabinet which may be installed at the factory and then folded down flat so as to take little room while the cabinet is being shipped.

It is another object of this invention to provide a stack which may be stamped from a flat sheet of flexible material.

It is another object of this invention to provide a novel reenforcing member around the edge of an otherwise flexible stack for a refrigerator.

Other objects and advantages of this invention will be apparent from a consideration of the drawings of which there is one (1) sheet and in which:

Fig. 1 represents a perspective view of a refrigerator cabinet showing my invention installed on the back thereof;

Fig. 2 is a horizontal section taken along the line 2—2 in Fig. 1 and looking in the direction of the arrows;

Fig. 3 is a vertical section taken along the line 3—3 in Fig. 1 and looking in the direction of the arrows;

Fig. 4 is a vertical section taken along the line 4—4 in Fig. 1 and looking in the direction of the arrows; and

Fig. 5 is a view of a corner of my stack, before it has been folded into shape, and showing how the stack may be cut from a flat blank of material.

In the embodiment of my invention illustrated, I have shown a refrigerator cabinet, generally indicated at 10, and having a back panel 12 which extends down the back of the cabinet only to the machine compartment as indicated at 14.

As is more clearly illustrated in Fig. 3, the refrigerator machine compartment is housed below the food compartment and is enclosed by the sides of the refrigerator. The back panel 12 has an inturned flange 16 at the bottom portion

thereof which supports a partition panel 18 for separating the machine compartment from the insulation 20 which surrounds the food compartment tank 22. Cross frame members 24 are provided near the bottom of the machine compartment and are supported from the cabinet by means of clips 26 which may be welded to the side panels of the cabinet. The cross frame members 24 support a metallic frame 28 which in turn supports a motor compressor unit 30 by means of the clips 32 and the springs 34.

Attached to the compressor frame 28 by any convenient means, such as welding, I have provided a pair of clips 36 which are arranged to support a condenser generally indicated at 38 by engagement with the tubes and fins of said condenser. The condenser 38 may be of the usual cross finned coil type having coils 40 and cross fins 42. I have shown the condenser to be made up of two sections and so provided with four inlet and outlet pipes 44.

Attached to the back panel 12, as by welding, are two angle irons 46 which are arranged in parallel vertical position. These angle irons act as supports for the stack 50 which is fastened to the angle irons by means of the metal screws 54 which pass through washers 52 and the stack, and then into threaded holes in the angle irons 46.

The stack 50 may be made up of paper board, imitation leather or some similar light and cheap material and may further be stamped from a flat piece of the material and then folded into shape by scoring the panel along the proper lines as is indicated at 52 in Fig. 5. The side panels 54 are cut longer at their outside end so that when the panel 54 is bent at right angles to the main or back panel 56, the side panel will have an edge extending downwardly from the back panel. The bottom panel 58 is then bent away from the plane of the back panel until it meets the edge of the side panels 54. I have provided a tab 60 on the bottom panel 58 which, when bent at right angles to the bottom panel, will lie alongside the side panels 54. The tabs 60 and the side panels 54 are punched, as at 62, to provide cooperating holes through which spring clips or fasteners 64 may be inserted. The clips 64 may be so designed that they may be forced through the holes 62 from the outside of the stack and will then spring out on the inside of the stack to hold the parts together without any connection being made on the inside of the stack.

The top of the stack is reenforced by a strip

65 of U-shaped metal which is fastened along the top edge of the stack by crimping its edges into the paper board or material of the stack as at 66. The reenforcing strip 65 is cut away at the top and inside of the corners of the stack so as to make the stack, as a whole, more flexible. Thus, the top and inside of the reenforcing strip stop short at 68 at each corner of the stack leaving only a strip 70 along the outside of the stack for connecting the sections of the reenforcing strip.

The side panels 54 of the stack are arranged to overlie the end fin on the condenser and to be positioned adjacent the ends of the coils as is indicated at 74. If the position of the condenser within the machine compartment is such that the condenser is not flush with the back of the cabinet the side panels may be provided with an extended portion 76 to pass into the machine compartment and meet the condenser.

From this construction it should be evident that the bottom panel member 68, when it is bent inwardly and clipped to the side panels 54, acts as a reenforcing member and stiffens the entire stack to maintain it in an open position. If the clips 64 are withdrawn and the bottom panel is folded out of engagement with the side panels, the entire stack may be folded sideways as is indicated by the dotted lines in Fig. 2.

This construction allows the stack to be installed at the factory and then shipped, without taking up too much room and thus requiring a larger packing case. The construction also eliminates any possibility of loss of the stack as the parts are firmly joined together.

It is to be understood that I intend this disclosure to be descriptive only and not limiting on my invention.

What I claim is:

1. In a refrigerator including a cabinet having an upwardly extending wall, means defining an opening in the vicinity of the lower portion of said wall adapted to communicate with a condenser for allowing passage therethrough of warm air from said condenser, means defining in combination with said wall a stack adapted to conduct warm air from said opening vertically, said means comprising a first panel portion spaced from and extending generally in parallel relation to said upwardly extending wall, additional panel portions extending from said rear panel portion inwardly to a position adjacent to said vertical wall, means for fastening said additional panel portions to said wall, said panel portions being laterally shiftable to bring said rear panel portion inwardly with respect to said rear wall for reducing the space occupied to facilitate shipping, an additional panel portion arranged to extend from the lower extremity of said rear panel portion at an angle to the horizontal to a position adjacent said upwardly extending wall and means for attaching said

additional panel portion at opposite extremities thereof to each of said inwardly extending panel portions for imparting rigidity to said stack.

2. In a refrigerator including a cabinet having a generally vertically extending wall, said wall being provided in the area of the lower portion thereof with an opening adapted to communicate with a condenser for allowing the passage therethrough of warm air from said condenser, means defining in combination with said wall a stack adapted to conduct warm air from said opening vertically, said means comprising a panel assembly including a first rear panel portion spaced from and extending inwardly parallel to said vertical wall, a pair of side panels extending from said rear panel portion to a position adjacent said vertical wall, means for fastening said side panels to said wall, said rear panel and side panels being laterally distortable about said fastening means to bring said rear panel inwardly with respect to said rear wall for reducing the space occupied to facilitate shipping, said panel assembly including further a bottom panel portion extending from the lower extremity of said rear panel at an acute angle to the horizontal to a position adjacent said vertical wall and the means for attaching said bottom panel adjacent the opposite extremities thereof to said respective side panels for imparting rigidity to said stack.

3. In a refrigerator including a cabinet having a generally vertically extending wall, said wall being provided with an opening in the area of the lower portion thereof adapted to communicate with a condenser for allowing the passage therethrough of warm air from said condenser, means in combination with said wall defining a stack assembly adapted to conduct warm air from said opening vertically, said means comprising a unitary piece of panel material including a rear panel portion spaced from and extending generally parallel to said vertical wall, a pair of side panel portions folded out of the plane of said first panel portion along generally vertical lines and extending from said first panel portion to a position adjacent said vertical wall to define with said wall a generally vertical conduit, means for fastening said side panels to said wall, said rear panel and said side panel being laterally distortable about said fastening means to bring said rear panel inwardly with respect to said rear wall for reducing the space occupied to facilitate shipping, and a bottom panel portion folded out of the plane of said rear panel portion along a generally horizontal line at the lower extremity of said rear panel portion and extending at an acute angle to the horizontal to a position adjacent said wall and means for attaching said bottom panel portion to said respective side panel portions for imparting rigidity to said stack when in installed position.

SAMUEL E. BICKLE.
